(57) **CLAIM**

The ornamental design for a refrigerator, as shown and described.

DESCRIPTION

Cross-reference is made to U.S. Design patent application Ser. No. 29/771,331, titled "Refrigerator", filed on the same day as the present application and all of which is expressly incorporated herein by reference.

FIG. 1 is a first perspective view of a design for a refrigerator;

FIG. 2 is a second perspective view of the design of FIG. 1;

FIG. 3 is a front view of the design of FIG. 1;

FIG. 4 is a top view of the design of FIG. 1;

FIG. 5 is a bottom view of the design of FIG. 1;

FIG. 6 is a first side view of the design of FIG. 1;

FIG. 7 is a second side view of the design of FIG. 1;

FIG. 8 is a first perspective view of the design of the refrigerator with the door in an open position;

FIG. 9 is a second perspective view of the design of FIG. 8;

FIG. 10 is a front view of the design of FIG. 8;

FIG. 11 is a top view of the design of FIG. 8;

FIG. 12 is a bottom view of the design of FIG. 8;

FIG. 13 is a first side view of the design of FIG. 8; and,

FIG. 14 is a second side view of the design of FIG. 8.

The stippling indicates an area which depicts contrast from the surrounding area.

The broken lines shown in the drawings are included for the purpose of illustrating the unclaimed boundary or unclaimed portions of the refrigerator. The broken lines form no part of the claimed design.
